US00D683083S

(12) **United States Design Patent**
Blizzard

(10) **Patent No.:** **US D683,083 S**
(b4) **Date of Patent:** ** *May 21, 2013

(54) **ANIMAL GARMENT**(75) Inventor: **Philip J. Blizzard**, Durham, NC (US)(73) Assignee: **Thundershirt, LLC**, Durham, NC (US)

(*) Notice: This patent is subject to a terminal disclaimer.

(**) Term: **14 Years**(21) Appl. No.: **29/424,308**(22) Filed: **Jun. 11, 2012****Related U.S. Application Data**

(63) Continuation of application No. 12/769,735, filed on Apr. 29, 2010, now Pat. No. 8,291,867.

(51) **LOC (9) Cl.** ..... **30-01**(52) **U.S. Cl.**USPC ..... **D30/145**(58) **Field of Classification Search** D30/152, D30/144, 151, 153, 154, 145; 119/702, 712, 119/792-798, 758, 760, 769, 770, 784, 815, 119/818, 856, 863, 864, 905, 907, 802, 857, 119/865, 725, 771; D21/805, 804; D3/217, D3/327, 271.2; D29/101.1, 101.5, 101.3; D24/190; D34/28; 54/71

CLAIM

The ornamental design for an animal garment, as shown and described.

DESCRIPTION

FIG. 1 is a top front perspective view of an animal garment having a flap facing in a first direction showing my new design.

FIG. 2 is a top front perspective view of the animal garment as shown in FIG. 1 and having the flap facing in a second direction showing my new design.

FIG. 3 is a top front perspective view of the animal garment as shown in FIG. 1 and having the flap partially cut-away showing my new design.

FIG. 4 is a top rear perspective view of the animal garment as shown in FIG. 1 showing my new design.

FIG. 5 is a top rear perspective view of the animal garment as shown in FIG. 2 showing my new design.

FIG. 6 is a top rear perspective view of the animal garment as shown in FIG. 3 showing my new design.

FIG. 7 is a top plan view of the animal garment as shown in FIG. 1 showing my new design.

FIG. 8 is a top plan view of the animal garment as shown in FIG. 2 showing my new design.

FIG. 9 is a top plan view of the animal garment as shown in FIG. 3 showing my new design.

FIG. 10 is a bottom front perspective view of the animal garment as shown in FIG. 1 showing my new design.

FIG. 11 is a bottom plan view of the animal garment as shown in FIG. 1 showing my new design.

FIG. 12 is a front elevation view of the animal garment as shown in FIG. 1 showing my new design.

FIG. 13 is a rear elevation view of the animal garment as shown in FIG. 1 showing my new design.

FIG. 14 is a front elevation view of the animal garment as shown in FIG. 2 showing my new design.

FIG. 15 is a rear elevation view of the animal garment as shown in FIG. 2 showing my new design.

FIG. 16 is a front elevation view of the animal garment as shown in FIG. 3 showing my new design.

FIG. 17 is a rear elevation view of the animal garment as shown in FIG. 3 showing my new design.

FIG. 18 is a right side elevation view of the animal garment as shown in FIG. 1 showing my new design.

FIG. 19 is a left side elevation view of the animal garment as shown in FIG. 1 showing my new design.

FIG. 20 is a right side elevation view of the animal garment as shown in FIG. 2 showing my new design.

FIG. 21 is a left side elevation view of the animal garment as shown in FIG. 2 showing my new design.

FIG. 22 is a right side elevation view of the animal garment as shown in FIG. 16 showing my new design; and,

FIG. 23 is a left side elevation view of the animal garment as shown in FIG. 16 showing my new design.
